UNITED STATES PATENT OFFICE.

JAMES E. SERRELL AND W. DAVIS, OF NEW YORK, N. Y.

LIFE-PRESERVER.

Specification of Letters Patent No. 18,869, dated December 15, 1857.

To all whom it may concern:

Be it known that we, JAMES E. SERRELL and WILLIAM DAVIS, of the city, county, and State of New York, have invented, made, 5 and applied to use a new and useful Improvement in Life-Preservers, which we term the "Ocean Floating-Jacket;" and we do hereby declare that the following is a full, clear, and exact description of the construction and operation of the same, reference being had to the annexed drawing, making part of this specification, wherein—

Figure 1, is a front elevation of the said jacket and Fig. 2, is a plan of the same.

15 Similar marks of reference indicate the same parts.

For preserving life from the perils of the sea, various characters of life preservers have been devised, and intended to surround 20 or be attached to the upper part of the body; and some of these have been formed of water proof material filled with air; but all these life preservers are more or less expensive and are, in most cases, too costly to 25 be purchased by the ordinary seaman.

The object of our invention is to obtain a life preserver that can be made or purchased by sailors and others at a small cost, and be efficient at all times, and can be worn in 30 times of danger without being in the way while performing the ordinary duties consequent on seafaring life.

We construct our ocean floating jacket of 35 canvas or other suitable material, in a form adapted to the person as at *a*, with a drawing cord or strap *b*, around the lower end, by which the jacket is drawn tight to the person at the waist, and the same may also be buttoned up the front as at *c*, *c*, *d*, *d*, are 40 the arm holes, and *e*, the neck of said jacket.

We provide two pockets *f* *f*, in front of

the jacket, and pockets *g* *g*, one under each arm, and also pockets *h*, *h*, on the back similar in shape to the pockets *f* *f*. These pockets are to be made of canvas or other suitable material; we however prefer that they be made of oiled canvas. Into each of these pockets we insert a float of the proper size and shape made in the following manner: We take a bladder or equivalent water 50 proof substance and fill the same with shavings and insert the same into the pockets and sew the same into place.

It will now be apparent that the jacket *a*, fitting the person loosely and the pockets 55 (*f*, *f*, *g*, *g*, *h*, *h*) being sewed onto the outside as shown the body will not be subjected to any pressure or strain from the floating material contained in said pockets, and the arms and body are entirely free to be used 60 in swimming; and the whole jacket will not be any hindrance to the performance of any work on board of a sinking ship before it be necessary to take to the water. Our jacket is cheap, convenient, durable, always 65 ready for use, easily put on and requires no inflation.

What we claim as our invention and desire to secure by Letters Patent is—

The manner herein described of forming 70 floats for the pockets of life preserving jackets, by filling bladders with shavings or equivalent material substantially as and for the purposes specified.

In witness whereof we have hereunto set 75 our signatures, this thirteenth day of October 1857.

JAMES E. SERRELL.
W. DAVIS.
